UNITED STATES PATENT OFFICE.

HALVOR GAARA, OF NEW YORK, N. Y.

CYLINDER-MACHINE.

962,208.

Specification of Letters Patent. Patented June 21, 1910.

Application filed November 15, 1907. Serial No. 402,251.

To all whom it may concern:

Be it known that I, HALVOR GAARA, a subject of the King of Norway, residing at New York city, in the county of New York and 5 State of New York, have invented certain new and useful Improvements in Cylinder-Machines, of which the following is a specification.

My invention relates to the manufacture 10 of wood pulp and paper and more especially to cylinder-machines. In order to save the very fine fibers contained in the water passing through the upper portion of the cylinder, while the latter slowly rotates, a series of 15 radially extending ribs is provided at the inner circumference of the cylinder, said ribs being disposed longitudinally of the cylinder and forming conduits for conducting the water outside of the cylinder, where it 20 can be utilized in different ways. In order that the other water collecting in the lower portion of the cylinder is practically free from fibers and "dust stuff", it is important that the level of the pulp-carrying water in 25 the tank containing the cylinder is kept as high as possible and always uniform. For accomplishing this end, either an automatic valve can be arranged in the conduit, through which the pulp-carrying water is 30 conducted into the tank containing the cylinder, or the tank can be provided with an overflow, whereby a uniform level in the tank is maintained.

For the sake of a better understanding, I 35 have illustrated my invention.

On the accompanying drawing, Figure 1 shows in a diagrammatic way a cylinder machine, the tank having connected therewith a supply pipe, in which an automatic 40 valve is provided. Fig. 2 shows a cylinder machine in connection with an overflow.

The tank 1 is divided by a partition wall 2 into two compartments A and B, the larger one A of which contains the cylinder 3, 45 which is secured to a shaft 4, rotatably journaled in suitable bearings. On its inner circumference, the cylinder 3 is provided with a continuous series of ribs 5, extending radially toward the center of the cylinder and 50 forming conduits 6. While the cylinder slowly rotates in the direction of the arrow,

the fibers contained in the water will be deposited on the outside of the cylinder. The fibers are then taken off by the couch-roll 7, held in contact with the cylinder, whereas 55 the water will pass through the cylinder and flow into the conduits 6, by means of which it is conducted outside of the cylinder into a receptacle 8 from where it may be conducted back to the pulp carrying water. Against 60 the couch-roll 7 bears the well-known scraper 9, whereby the excess of pulp is removed and delivered into the compartment B.

As seen in Fig. 1, a supply pipe 10 is connected with the tank, in which pipe is provided an automatic valve *b* of any desired 65 construction. The valve is so arranged that it will always maintain a uniform level in the tank. The construction of such valves being well known, it will not be necessary 70 to describe the same.

In Fig. 2, similar reference numerals designate similar parts, as those shown in Fig. 1. In this form of my invention, however, there is interposed in the supply-pipe 10 a 75 smaller tank 11 provided with an overflow 12. In the cylinder tank and in the tank 11 the same level is always maintained. If the level rises above a certain height, the pulp-carrying water in the smaller tank 11 will 80 escape by way of the overflow 12 and flow into a trough or receptacle 13, from where it may be conducted back to the pulp-vat. In the supply-pipe 10, a shut-off valve 14 is provided in case the pulp-carrying water 85 is to be supplied to the cylinder-tank directly. To this end, a second supply pipe 15 is connected with the lower end of the cylinder tank, which pipe is provided with a shut-off valve 16. Of course, a plurality 90 of cylinder tanks can be connected with a common overflow tank or a common automatic valve as that shown in Fig. 1, whereby the level in all the cylinder-tanks is maintained uniform. 95

What I claim and desire to secure by Letters Patent is:

In a cylinder machine the combination with a tank divided into two compartments, and a cylinder rotatably mounted in one 100 of said compartments and provided on its inner periphery with conduits for the water

passing through the upper portion of said cylinder, of a water supply conduit terminating in said tank and a second tank disposed in said supply conduit on a level with
5 the said first tank, and provided with an overflow for the purpose specified, and a second water supply conduit connected with the cylinder containing tank, independently

of said first supply conduit, and a shut-off valve in each of said supply conduits. 10

In testimony whereof I affix my signature in presence of two witnesses.

HALVOR GAARA.
